UNITED STATES PATENT OFFICE.

HUGH M. STOLLER, OF NEW YORK, N. Y., ASSIGNOR TO WESTERN ELECTRIC COMPANY,
INCORPORATED, OF NEW YORK, N. Y., A CORPORATION OF NEW YORK.

POWER SYSTEM FOR RADIO APPARATUS.

1,411,814.

Specification of Letters Patent.

Patented Apr. 4, 1922.

Application filed April 30, 1918. Serial No. 231,586.

To all whom it may concern:

Be it known that I, HUGH M. STOLLER, a citizen of the United States, residing at New York, in the county of New York and State 5 of New York, have invented certain new and useful Improvements in Power Systems for Radio Apparatus, of which the following is a full, clear, concise, and exact description.

- 10 This invention relates to power systems, and more particularly it relates to power systems for radio apparatus of the type including vacuum tubes or other discharge devices having electrically heated cathodes and 15 designed for use where economy of space and lightness are of prime importance, as in aeroplanes. A great obstacle to radio transmission from aeroplanes has been the weight of the power systems required.
- 20 The primary object of this invention is to produce a power system for such radio apparatus which combines practical utility with the highest degree of economy in space and weight.
- 25 With certain arrangements of vacuum tubes of the three-electrode type for transmission of radio messages from aeroplanes, it is necessary to provide a filament heating source of approximately 10 volts and an 30 anode-cathode source of from 200 to 600 volts. Both sources of electromotive force must be reasonably free from alternating current components and likewise must be of substantially constant voltage during the 35 period required for signaling purposes; otherwise continual manual adjustment as, for example, by means of resistances, would be necessary.

In fulfilling the above and other requirements apparatus has been designed in accordance with the accompanying drawings in which Fig. 1 is a conventional diagram of one embodiment of my invention; Fig. 2 is a diagram of a modified form; and Fig. 3 is 45 an explanatory diagram of the current filter shown in both Figs. 1 and 2.

In Fig. 1 numeral 1 represents a suitable source of electric energy, such as a storage battery adapted to give a considerable output at slightly above ten volts. Across battery 1 is connected the motor winding of a dynamotor or motor-generator in which numeral 2 represents the series winding, 3 the shunt winding and 4 the armature mechanically connected to the generator armature

5. In a preferred form all the windings are on a common armature. The generator 5 produces a current of sufficiently high potential, for example, 500 volts, to provide space current between the filaments 8 and 60 anodes 9 of a set of vacuum tubes 10. Across battery 1 are placed the filaments or cathodes of tubes 10 in any suitable manner so that the cathodes may be heated. Associated with the tubes 10 will be such elements as are 65 necessary to constitute a radio system of any desired kind. Since the details of such systems are known to those skilled in the art, they are not herein illustrated. Choke coil 12, such as is usually used in series with the 70 source of anode-cathode current in order to prevent high-frequency currents from being short-circuited through the direct current source, is provided in conductor 6. Conductor 7 forms a common negative terminal. 75

In the arrangement as so far described, the fluctuations induced by the reaction of the armature and by the commutator segments, particularly the latter, will tend to create undesirable fluctuations of audible frequency in the output of the vacuum tubes 80 10. The commutator segments, for example, will tend to produce a fluctuation depending on their number and speed of rotation of from 500 to 5000 cycles, and thus 85 produce a noise of the same frequency in the output. There are filters of types well known in the art, as for example, those described in Campbell Patent No. 1,227,113, granted May 22, 1917, which could be used 90 to remedy this difficulty, but the capacities and inductances used in such filters constitute too great a bulk and weight to be carried upon aeroplanes. A filter is here used consisting of inductance coils 13 in series 95 and resistances 14 across the line. Although less efficient in one respect since direct current energy is wasted in the resistances, this type of filter accomplishes the desired purpose and consists of elements having minimum bulk and weight, and is much less expensive.

For a particular description of the filter reference is made to Fig. 3. The direct current machine 4, owing to the action of its 100 commutator segments, will act also as a source of superimposed alternating current of, for example, 600 cycles, the direct current will pass through and heat the filaments 8, but with some loss through the resistances 110

14. Suppose that the alternating voltages at points *a*, *b*, *c* and *d* are respectively represented by E_0 , E_1 , E_2 and E_3 ; that the impedances of coils 13 to the said alternating voltages are respectively represented by Z_0 , Z_1 and Z_2 ; that the respective resistances of elements 14 are R_1 and R_2 ; and of filaments 8 is R_3 ; then if Z_0 , Z_1 , etc. are large compared with R_1 and R_2 , etc., the following 10 equation will be approximately true:

$$E_3 = E_2 \frac{R_3}{Z_2} = E_1 \frac{R_2 R_3}{Z_1 Z_2} = E_0 \frac{R_1 R_2 R_3}{Z_0 Z_1 Z_2}$$

15. Thus, for a given frequency, if $R_1 = \frac{Z_0}{12}$,

$$R_2 = \frac{Z_1}{12} \text{ and } R_3 = \frac{Z_2}{24}, \text{ the alternating voltage}$$

20. E_3 will be approximately $\frac{E_0}{3456}$. The loss of direct current energy will not be serious, because the source 1 is necessarily designed to have a high output at a low voltage for a comparatively short time. A greater or 25 less number of filter elements may be used if desirable.

30. Since the battery 1, in common with other storage batteries, has a rapidly falling terminal voltage as it becomes discharged, it is necessary in some cases to compensate for this by a ballast resistance 15 (Fig. 1). For this purpose it is desirable to use an iron wire sealed in an atmosphere of inert 35 gas in an airtight vessel, with the terminals connected into the 10-volt circuit. When properly constructed the resistance of this device is comparatively high at maximum battery voltage, but falls rapidly as the voltage decreases slightly therefrom and 40 hence tends to keep the voltage impressed across the filaments substantially constant.

45. In Fig. 2 is shown a modified form in which the battery or source 1 operates a motor-generator which has two output windings, one of ten volts for heating the filaments, across which a filter 13, 14 is placed, as in the arrangement of Fig. 1, and a higher voltage winding of 500 volts for the anode-cathode current of the vacuum tubes 50. The motor-generator of this arrangement is preferably a constant speed machine, and its output voltages will be substantially constant at ten and 500 volts, respectively.

55. The device 15 of Fig. 1 is therefore not needed in this arrangement.

It should be noted that lightness and small volume are the features which are considered of paramount importance in these systems, and are obtained at some 60 sacrifice either of power efficiency or of ability for sustained service over long periods, or both.

65. The arrangements shown are illustrative only, and other modifications may be devised by those skilled in the art which will

fall within the scope of the invention as expressed by the appended claims. While described as part of a transmitting system for an aeroplane, certain features of the invention will be found useful in other places 70 where a power plant of limited weight and volume is required. Since the current discharge tubes 10 may form elements of a receiving or high frequency generating system in any of the known arrangements employing such devices, it is obvious that the invention as applied to signaling stations is not limited to transmitting systems. Filters of the type shown are particularly useful 75 in receiving systems.

80. What is claimed is:

1. The combination with the elements of a thermionic vacuum tube system which requires currents of high and low voltage respectively, for short periods of operation 85 only, of a power system therefor comprising a battery of said low voltage, a motor operated by said battery, a generator of said high voltage operated by said motor, and connections from said battery and said generator to said elements respectively.

2. In a radio system, a discharge device having a cathode, a source for supplying current at a low voltage to heat said cathode, a generator, circuits whereby said source 95 operates said generator, and circuits whereby said generator supplies space current at a high voltage to said discharge device.

3. In a radio system, a discharge device having a cathode, a battery and line conductors for supplying current to heat said cathode, a generator, circuits whereby said battery operates said generator, circuits whereby said generator supplies space current to said discharge device, and a filter 100 associated with said line conductors comprising inductances in series with and a resistance in shunt to said cathode.

4. In a system for radio communication, a source of current, means whereby said 110 source supplies a high voltage to one path in said system and a low voltage to another path therein, said means reacting on said second path to produce fluctuating current therein, and a filter associated with said 115 second path consisting of a number of inductances in series with and a number of resistances in shunt to said path.

5. In combination in a radio system for use upon an aeroplane, a battery, a motor-generator and a vacuum tube, means whereby said battery operates said motor-generator, means whereby said battery supplies low voltage current to said tube, and means whereby said motor-generator supplies high 125 voltage current to said tube.

6. In combination in a radio system for use upon an aeroplane, a battery, a motor-generator and a vacuum tube, means whereby said battery operates said motor-gen- 130

erator, means whereby said battery supplies low voltage current to said vacuum tube, means whereby said motor-generator supplies high voltage current to said tube, means 5 whereby said motor-generator reacts on said low voltage supply, and means for rendering negligible the effect of said reaction.

7. In a signaling system the combination of two energy consuming load paths requiring different voltages, a single source of 10 energy for supplying said paths, a direct

connection between said source and one of said paths, a direct current voltage transformer connected between said source and the other of said paths, means whereby said 15 voltage transformer causes an undesirable reaction upon one of said paths, and a filter for eliminating the effect thereof upon said path.

In witness whereof, I hereunto subscribe 20 my name this 26th day of April, A. D., 1918.

H. M. STOLLER.
